CHILD'S PUSH TOY

Ronald J. Campanell, Village of Pine Run,
Blackwood, N.J. 08012

Filed Feb. 27, 1974, Ser. No. 446,537

Term of patent 3½ years

Int. Cl. D21—01

U.S. Cl. D34—15 D

FIG. 1

FIG. 2

FIG. 3

FIG. 4

FIG. 5

FIG. 1 is a side elevation of a child's push toy showing my new design;

FIG. 2 is a front elevational view thereof;

FIG. 3 is a top plan view thereof;

FIG. 4 is a rear elevational view thereof; and

FIG. 5 is a bottom plan view thereof.

I claim:

The ornamental design for a child's push toy, substantially as shown.
